CLAIM

We claim the ornamental design for a tray for industrial vehicle, as shown and described.

DESCRIPTION

FIG. 1 is a front isometric view of a tray for a lift truck in a first configuration;

FIG. 2 is a front view of the tray for a lift truck of FIG. 1;

FIG. 3 is a back view of the tray for a lift truck of FIG. 1;

FIG. 4 is a left view of the tray for a lift truck of FIG. 1;

FIG. 5 is a right view of the tray for a lift truck of FIG. 1;

FIG. 6 is a top view of the tray for a lift truck of FIG. 1; and,

FIG. 8 is a front isometric view of the tray for a lift truck of FIG. 1 showing additional environmental components.

The broken lines shown in FIG. 8 are included for the purpose of illustrating environment and form no part of the claimed design.
